UNITED STATES PATENT OFFICE.

BURNIE J. CRAIG, OF CLEVELAND, OHIO, ASSIGNOR TO THE AMERICAN MULTIGRAPH COMPANY, OF CLEVELAND, OHIO, A CORPORATION OF OHIO.

ASSEMBLED PRINTING FORM.

Application filed August 20, 1921. Serial No. 493,830.

To all whom it may concern:

Be it known that I, BURNIE J. CRAIG, a citizen of the United States, residing at Cleveland, in the county of Cuyahoga and 5 State of Ohio, have invented a certain new and useful Improvement in Assembled Printing Forms, of which the following is a full, clear, and exact description, reference being had to the accompanying drawings. 10 This invention relates to assembled printing forms wherein the characters are pressed or embossed on strips which are removably secured on a holding member. The invention is adapted for use with address plates 15 which comprise holding members having means for securing an address printing member thereon.

One of the objects of the invention is to provide simple effective means for holding 20 an embossed strip or like member on a plate. A more specific object of the invention is to so construct the holding or mounting plate to accomplish a reinforcing of the plate holder by means which provide a continuous ele- 25 vated support for the printing characters.

Additional objects of the invention will be apparent from the following specification taken in connection with the accompanying drawings wherein Fig. 1 is a perspective 30 view partly in section showing a printing plate embodying my invention; Fig. 2 is a top plan view of the plate; Fig. 3 is a section on line 3—3 Fig. 2; Fig. 4 is a section on line 4—4 Fig. 2; and Fig. 5 is a section on line 5—5 Fig. 2.

Referring to the drawings by reference 35 characters I have shown a printing plate at 10. This plate may be of metal or other material and may be adapted for use in any 40 type of holder, for instance, one of the type shown in the prior application Serial No. 410,710, filed September 16, 1920 by Clifton Chisholm.

The plate 10 is shown as provided with a 45 plurality of longitudinally extending ribs or corrugations 12, which may extend substantially parallel with side edges of the plate and are shown as terminating at spaced distances from either end of the plate.

50 Oppositely disposed projections 14 are shown at spaced intervals along the corrugations 12. These projections may be formed by slitting the material of the plate along opposed curved lines 16, and then pushing the

portions defined by the curved slits above the 55 plane of the plate holder as shown in Fig. 3.

It will thus be seen that the corrugations 12 provide continuous elevated supports for a printing character arranged thereon and that the projections provide shoulders along 60 side this elevated bed, which overhang the plate and which may serve to hold a printing character in position. The printing characters used with my plate may comprise embossed strips 20 having the characters 21 65 raised thereon. These strips 20 are provided with opposed, inwardly directed, flanges 22 which are adapted to engage beneath the projections 14 of the plate 10 and to be held in place thereby. A printing strip of the 70 character described is shown in application Serial No. 462,256 filed April 18, 1921, by Clifton Chisholm.

Any number of printing strips may be provided on the plate. These may each comprise but a single line of characters or, if desired, two or more lines of characters may be used on the same strip. In the latter case the character strip would overlap two or 75 more rows of projections.

80 My invention is adapted for use in connection with plate holders for addressing machines or in rotary printing presses wherein the printing characters are held upon rotat- 85 ing printing drums.

Having thus described my invention, I claim:

1. A plate having a longitudinal rib thereon to provide a continuous elevated panel and having holding projections struck from 90 said plate adjacent said panel.

2. A holder for an impression member comprising a plate having a plurality of longitudinally spaced projections thereabove and having a continuous supporting panel 95 for the printing member associated with said projections.

3. A printing member comprising a holder having a continuous strip supporting rail thereon, said rail having spaced 100 lateral projections struck therefrom and adapted to be engaged by a printing member.

4. A plate having a longitudinal channel 105 therein, said channel providing an elevated panel, tongues struck from said plate adjacent said panel and a printing strip having a portion thereof secured to said tongues.

- 2
5. A plate comprising a body portion having a strip supporting rail raised into a plane above the body portion to provide a continuous support, said rail being provided 5 with spaced lateral projections, and a printing strip having overhanging edges engaging said projections.
6. A printing strip holder having spaced projecting tongues thereon, said tongues 10 facing in opposite directions and arranged above the body of the holder, said tongues being joined by a web also raised above the body of the holder, the portion intermediate the tongues being elevated above the 15 holder.
7. A holder comprising a plate having a plurality of rows of alternately facing spaced projections thereon lying in a plane parallel to the body of the holder and a continuous 20 rib extending lengthwise of the holder, said projections having their roots adjacent said rib.
8. A character printing strip holder having a row of projections thereon, said projections 25 being severed from the holder and raised thereabove to provide overhanging portions, there being a continuous longitudinal elevated bed above the plane of the plate holder, intermediate the projections.
30. 9. A printing strip holder having a row of opposed spaced projections pressed therefrom, each projection being connected with the holder only by two portions which are

narrower than the head of the projections and are located respectively at the opposite 35 edges of the projections and have a portion thereof in the plane of the top of the projections to provide a continuous elevated bed.

10. A character printing strip holder having a row of projections thereon, said projections being arranged in pairs and being disconnected from the holder to provide overhanging portions, the portions intermediate the pairs of projections being arranged 45 to provide longitudinal elevated beds above the plane of the plate holder, and a printing strip adapted to overlie said projections and having inwardly flanged sides adapted to extend beneath said overhanging portions. 50

11. The combination of a printing strip holder having a body part with a plurality of engaging members thereon, each member including a central part raised above the plane of the body portion, and two oppositely disposed engaging portions, the portion of the holder intermediate said central portions being raised into the plane of said portions whereby a continuous supporting panel is provided, and an impression strip 60 adapted to overlie the elevated bed and being secured to the engaging members. 55

In testimony whereof, I hereunto affix my signature.

BURNIE J. CRAIG.
